FRANK ENGLISH, OF FRESNO, CALIFORNIA.

LIFT-PUMP.

1,294,069.

Specification of Letters Patent. Patented Feb. 11, 1913.

Application filed September 24, 1917. Serial No. 182,673.

To all whom it may concern:

Be it known that I, FRANK ENGLISH, a citizen of the United States, residing at Fresno, in the county of Fresno and State of California, have invented new and useful Improvements in Lift-Pumps, of which the following is a specification.

This invention relates to lift pumps, and has for its object to provide a pump of this character capable of lifting water from increased depths and in greater volume than pumps heretofore used for this purpose.

I accomplish this object by means of a stage principle of operation wherein a plurality of separate suction members are arranged at different points in the depth of the shaft for lifting the water in successive steps.

One form which my invention may assume is exemplified in the following description and illustrated in the accompanying drawings, in which—

Figure 1 shows a side elevation of the device, partly in section.

Fig. 2 shows an enlarged detail view in section of the pump shaft.

Fig. 3 shows a sectional view of two of the valves which control adjacent suction pipes.

A vacuum tank is indicated at 10 from which air is exhausted by means of a pump 11. Connected to the tank, each by a separate pipe 12, are a series of controlling valves 13, five in the present instance, although any number may be utilized. Each valve in turn has a pipe leading from it, the pipes being designated 1, 2, 3, 4 and 5 respectively. Pipe 1 leads to a pump head 14 and pipes 2, 3, 4 and 5 lead to different points on a column or shaft 15, ranging from top to bottom. The shaft opens into the pump head at its upper end by means of an elbow 16 and the length of the shaft is divided into separate compartments numbered 6, 7, 8 and 9 respectively by means of annular partitioning members 17. Each of the pipes 2, 3, 4 and 5 lead to a different compartment of the shaft.

The partitioning members 17 have beveled openings gradually decreasing in diameter from top to bottom, seated in each of which is a bevel plate 18 fixed upon the upper end of a tube 19. Each of the tubes is open at its upper end and projects below to a point near the bottom of the compartment where it is provided with an upwardly opening valve 20. The bottom of the shaft is shown terminating short of the water

level of the well and a valved tube 21 similar to tubes 19 and suspended in the same manner extends into the water 22 of the well.

The controlling valves 13 may be of any suitable arrangement, their function being to intermittently open the suction pipes to the atmosphere. As shown in Fig. 3, the valves comprise each a chamber 23 with which one of the pipes 12 communicates at the upper end and one of the pipes 1, 2, 3, 4, 5 communicates at one side. At the lower portion of the chamber is an opening 24 for communication with the atmosphere. A rotary valve 25 is fitted within the chamber and in its different positions puts the suction pipe in communication either with the vacuum tank or with the outside atmosphere. Adjacent valves as seen in Fig. 3 are so set that when one is open to the atmosphere the other is open to vacuum. Therefore when pipes 1, 3 and 5 are exerting a suction the remaining pipes are open to atmosphere.

Any suitable actuating mechanism may be provided for the controlling valves, but preferably one such that the movement of the valves shall be rapid. In the present instance, I show an outside crank arm 26 for turning the valve 25 and all five crank arms 26 are connected to a single rod 27 which in turn connects with one arm of a bell crank lever 28, the other arm of which is provided with a weight 29. A reciprocating rod 30 has pins 31 on opposite sides of the weighted arm to rock the latter back and forth over its dead center point. A second bell crank lever 32 actuates the rod 30 through the medium of an eccentric and strap 33 driven by the pump 11. When the reciprocating rod 30 is moved in either direction far enough to carry the weighted arm past its dead center the latter acts by gravity quickly to complete the movement of the controlling valves.

In operation, and assuming the pump is properly primed and that the controlling valves for pipes 1, 3 and 5 are in position to permit the vacuum to act on the latter, then the pipe 5 will fill its compartment with water through the tube 21 from the well below and pipe 3 will fill its compartment from the compartment below and pipe 5 will fill the pump head from the top compartment. In the mean time, pipes 2 and 4 are open to the atmosphere and no resistance is offered to the depletion of their compartments by the overlying suction pipes. Im-

mediately the suction pipes have filled their compartments the controlling valves are so timed as to be actuated and quickly reverse their position so that pipes 2 and 4 are now 5 on the vacuum and 1, 3 and 5 are open to the atmosphere. Thus water is lifted from compartment to compartment in successive stages, making possible the pumping of the water from greatly increased depths and in 10 greater volume.

The head 14 preferably discharges by gravity through a flap valve 34. The purpose of having the tubes 19 and 21 suspended from bevel seated heads, each of a different diameter, is to permit easy removal of these parts. Each tube is shown as having a bail 35 at its upper end to permit a grab hook to engage it whereby to lift the tube and head from the shaft. The fact that the apertures in the partition plates 17 increase in diameter from bottom to top permits these beveled heads from below to pass through the overlying partition plates quite readily. The elbow 16 is detachable from the pump head and shaft, and is, of course, removed when it is desired to lift the tubes from the shaft as above explained.

Various changes in the construction and arrangement of the several parts herein shown and described may be employed without departing from the spirit of my invention as disclosed in the appended claims.

Having thus described my invention, what I claim and desire to secure by Letters Patent is:

1. In a lift pump, a shaft divided throughout its length into separate compartments, a vacuum tank, a vertical series of outlet pipes leading from the tank, a vertical series of valves connected to the pipes, suction conduits connecting the valves to the respective compartments, and adapted to be alternately connected to the respective outlet pipes and the atmosphere through the

valves, a common actuator for the valves, an exhaust pump, and a weighted lever connected to the actuator and operable by the pump to oscillate beyond dead center for moving the actuator.

2. In a lift pump, a shaft partitioned 50 throughout its length into a plurality of separate compartments, each partition having a vertical opening of larger diameter than the opening in the underlying partition, a head fitting each partition opening 55 and removable upwardly through the next superposed partition opening, a valved tube suspended from each head, and suction means communication with the compartments. 60

3. In a lift pump, a shaft divided throughout its length into a plurality of separate compartments, each comprising an annular partition plate fixed in said shaft, a head having a beveled seat within said plate, a tube suspended from said head and a valve in said tube, and suction means communicating with each of said compartments. 65

4. In a lift pump, a shaft divided throughout its length into a plurality of separate compartments, each comprising an annular partition plate fixed in said shaft, a head having a beveled seat within said plate, a tube suspended from said head and a valve in said tube, suction means communicating with each of said compartments, said bevel seated members being of decreasing diameter from top to bottom and means whereby the suspended tube and head may be engaged by a grab hook to lift the same upwardly through the shaft. 80

In testimony whereof I have hereunto set my hand in the presence of two subscribing witnesses.

FRANK ENGLISH.
